CLAIM

The ornamental design for a tape measure holder, as shown and described.

DESCRIPTION

FIG. 1 is a side perspective view of a tape measure holder showing my new design; and,

FIG. 2 is a side perspective view of the tape measure holder with a tape measure attached.

The broken lines showing of the tape measure in FIG. 2 is for the purpose of depicting the tape measure holder with the tape measure attached and forms no part of the claimed design.

1 Claim, 2 Drawing Sheets

FIG. 1

FIG. 2
